CLAIM

The ornamental design for a security container for a citizens band radio, substantially as shown.

DESCRIPTION

FIG. 1 is a perspective view of a security container for a citizens band radio showing my new design in open condition;

FIG. 2 is a left side elevation view thereof in closed condition and on a reduced scale;

FIG. 3 is a front elevation view of FIG. 2;

FIG. 4 is a rear elevation view of FIG. 2;

FIG. 5 is a top plan view of FIG. 2; and

FIG. 6 is a bottom plan view of FIG. 2.
